FRANK W. MERRITT AND ALFRED E. WATTS, OF DULUTH, MINNESOTA.

LEVEL-REGISTERING MEANS.

1,422,118.

Specification of Letters Patent. Patented July 11, 1922.

Application filed April 4, 1921. Serial No. 458,393.

To all whom it may concern:

Be it known that we, FRANK W. MERRITT and ALFRED E. WATTS, citizens of the United States, residing at Duluth, in the 5 county of St. Louis and State of Minnesota, have invented certain new and useful Improvements in Level-Registering Means, of which we do declare the following to be a specification.

10 Our invention relates to level registering means, and has for its object the provision of simple and convenient means for determining whether a ship is level or properly trimmed, and, if not, how much out of level 15 she is. Said invention may be applied longitudinally of the ship to determine her longitudinal trim, or transversely of the ship to determine her transverse trim. It consists of the constructions, combinations 20 and arrangements of parts hereinafter described and claimed.

In the accompanying drawings, Fig. 1 is a transverse diagrammatic sectional view of the hull of a ship equipped with our invention. Fig. 2, is a fragmentary central transverse sectional view of said ship, showing one end of our said invention in retracted or closed position thereon. Fig. 3, is a longitudinal section of the hereinafter described 30 housing. Fig. 4, is a longitudinal side elevation of our said invention; showing the same in retracted position in solid lines, and in extended or operative position in broken lines. Fig. 5, is a central vertical 35 section, partly in side elevation of a gauge forming part of our said invention, and Fig. 6, is a top plan of a locking ring.

In the drawings, A is the hull of a vessel, or ship of any suitable structure preferably 40 including an outer skin 1, an inner skin 1^a, a deck 1^b, and a transversely disposed deck beam 1^c. Positioned below and preferably near said deck, where it will be out of the way, is a pipe 2, which extends nearly across 45 said vessel to points near its opposite sides. Pivotedly connected at one end to each end of said pipe 2 and communicating therewith are corresponding swing joints 2^b, 2^c, to the opposite ends of which are pivoted 50 to the opposite ends of said swing joints 2^b, 2^c, respectively. On the opposite ends of said swing joints 2^b, 2^c, and communicating therewith are pivotally mounted vertically extending level glasses or 55 gauges 3, 3, of any suitable construction adapted to extend upwardly through suitable apertures in the deck of the vessel and

into or through a housing 4, mounted on said deck.

Each of said gauges preferably comprises an interior glass tube 3^b; a tubular inner 60 case 3^a, concentric with said glass tube and having an elongated sighting aperture formed in one side for viewing said glass; packing rings 3^c, 3^d, between said glass tube and inner case; retaining rings 3^e positioned 65 above and below said packing rings, said retaining rings being preferably screwed into said inner casing tube; an exterior tubular casing 3 adapted to turn on its longitudinal axis and having an elongated aperture 70 formed in one side adapted in operative position to register with the viewing aperture in said interior case; a top plug or cap 3^f adapted to screw into said interior case and to overlap the upper end of said exterior 75 case, said top plug having an air vent 3^g formed therein, a locking ring 3^f adapted to screw on to the lower end of said outer case; a coupling 3^h adapted to screw into said interior case and into the end of the 80 corresponding one of said swing joints 2^c; and a scale marked or positioned on said gauge for reading the same. Mounted upon said deck above said apertures therein are 85 housings 4, 4, respectively, of any suitable construction, each preferably comprising a body portion 4 and a cover 4^a; said body portion has an aperture 4^b formed therein for the passage of the corresponding gauge 3. Concentric with said aperture 4^b said 90 body portion has an internal annular groove 4^c formed therein a short distance from its lower end, connecting with which groove are downwardly directed slots 4^d through which the ears 3^e of said locking ring 3^f are adapt- 95 ed to pass to said groove. Said passage 4^b is enlarged at its upper end whereby an annular shoulder 4^e is formed in said body portion below said cover, upon which shoulder the upper end of said gauge is adapted 100 to rest below said cover when said gauge is in lowered position.

In operation, the pipe 2 and said swing joints and part of each of said gauges are 105 filled with a suitable fluid, preferably a non-freezing fluid, and the tops of the gauges are closed except said air vents 3^g. In normal retracted position, the gauges are lowered until their tops are within said housings, and the covers are screwed or otherwise se- 110 cured on said housings. When it is desired to read the gauges, the covers of the hous-

ing are removed and the gauges are drawn up until the ears of the locking ring register with the groove 4^c, whereupon the external case 3 is given a quarter turn which operates to swing said ears into said groove to support the gauge. The turning of said external case also brings the viewing slot therein into registration with the viewing slot or aperture in said case 3^a. The standing of the fluid in the opposite gauges is then compared, and the extent, if any, of the ship's list, or divergence from level is observed, it being obvious that the fluid in the gauge on the lower side will rise, and that it will fall in the gauge on the higher side. It is obvious that the swing joints are used to obtain flexibility of connection between the gauges and said pipe 2. If desired, hose may be used in place of said swing joints, but we prefer to use the swing joints because of their greater durability. When it is not desired to read the gauges, the exterior case is given a reverse quarter turn to bring the ears of the locking ring into registration with said slots 4^d and so that the viewing slot or aperture in the casing 3^a and the glass 3^b will be covered and protected by the wall of the case 3. The gauge is then lowered until its upper end rests upon the shoulder 4^d, and said cover 4^a is replaced on said housing. The structure is thus fully protected from injury, and said housings

from leakage, and the deck is substantially clear. Advantage is preferably taken of the space between the two skins of the ship to 35 so position the movable parts of the device that it will be protected and substantially out of the way of other devices and operations aboard ship.

What we claim is:—

40 The combination with a vessel including a hull and a deck, a fluid reservoir having flexible terminals at its opposite ends, a vertically disposed fluid operated level gauge mounted upon each of said terminals and 45 adapted to communicate therewith, said gauges being adapted to stand so that the zero or central horizontal gauge lines on both of them will be in the same horizontal plane when said vessel is level, housings mounted 50 on said deck in registration with said gauges, said gauges being adapted to normally extend into said housings and in operation to extend upward through said housings, and means for supporting said gauges in raised 55 position.

55 In testimony whereof, we hereunto affix our signatures, in presence of two witnesses.

FRANK W. MERRITT.
ALFRED E. WATTS.
